ATTORNEY.

UNITED STATES PATENT OFFICE.

EMIL DEISTER, OF FORT WAYNE, INDIANA, ASSIGNOR TO DEISTER MACHINE COMPANY, OF FORT WAYNE, INDIANA, A CORPORATION.

ORE-CONCENTRATOR.

1,382,275.

Specification of Letters Patent. Patented June 21, 1921.

Application filed December 26, 1919. Serial No. 347,509.

To all whom it may concern:

Be it known that I, EMIL DEISTER, a citizen of the United States, residing at Fort Wayne, in the county of Allen and State of Indiana, have invented new and useful Improvements in Ore-Concentrators, of which the following is a specification.

The invention relates to ore concentrators and particularly to such concentrators which 10 are differentially reciprocated and transversely inclined downwardly in operating position.

The object of the invention is to provide a concentrating table having large capacity 15 and high efficiency and in which a novel form of riffling is used which adds greatly to the efficiency of the table.

In the accompanying drawings I have 20 illustrated an embodiment of the invention in which—

Figure 1 is a plan view of the deck of a concentrating table constructed in accordance with the invention;

Fig. 2 a cross-sectional view on line 2—2 25 of Fig. 1;

Fig. 3 a cross-sectional view on line 3—3 of Fig. 1;

Fig. 4 a cross-sectional view in an enlarged scale on line 3—3 of Fig. 1;

Fig. 5 a plan view of the deck of the table 30 illustrating a modification of the riffling thereon;

Fig. 6 a cross-section view on line 6—6 of Fig. 5 in an enlarged scale; and

Fig. 7 a side elevational view of one of 35 the riffles illustrated in Fig. 5.

Referring to the drawings, 10 indicates the deck of a concentrating table, 11 being the head motion end of the same, 12 the 40 feed and dressing water side, 13 the concentrates discharge end and 14 the tailings discharge side. The arrow 15 indicates the direction of differential reciprocation of the deck and the approximate point of attachment of the driving mechanism to the deck. The body of the deck is covered with linoleum 16 or other suitable material, and its 45 surface is formed in three sections A, B and C. Section C, the plateau, is elevated above section A and section B slopes upwardly from section A to section C, the coterminous lines a b and c d of section B and the other two sections respectively being preferably parallel and oblique to the line of reciprocation of the table.

Main riffles 17 are suitably secured to the deck over the linoleum and they extend in the direction of travel of the concentrates toward the concentrates discharge end 13 of the deck, their forward ends terminating on 60 the oblique coterminous line c d, which line indicates the rear edge of section C. Each main riffle 17 is beveled on its under side, as at 18, where the same contacts with section B, as shown in Figs. 2 and 7, and it is preferably beveled off on its lower side at its forward end, as shown in Figs. 1 and 5, said lower side of the riffle being that facing the tailings discharge side of the deck. As shown in Fig. 4, a portion, as 19, of the top 70 surface of each main riffle is parallel to the surface of the deck and the remainder, as 20, of said top surface slopes downwardly toward the tailings discharge side of the deck, the upper side 21 and lower side 22—the opposite sides of each riffle—being substantially at right angles to the surface of the deck. Hence the upper side 21 of each main riffle is higher than its opposite or lower side, and each said riffle is wider than it is 80 high.

The main riffles, constructed as above described, are most suitable for treating material in which the greater percentage thereof ranges in size from one-quarter inch down 85 to thirty mesh. As the pulp flows over the riffles in the direction indicated by arrow 23, Fig. 4, the upper side or wall 21 of each riffle retards the flow of the pulp sufficiently to cause a portion of the slope 20 of the riffle 90 above it to be flooded with water thereby covering the upper edge of the lower side or wall 22 of the latter riffle, and preventing a fall of water over said edge into the trough or channel immediately above said upper 95 wall 21. Stratification of the minerals begins on the portion 19 of each main riffle and the sloping portion 20 permits the concentrates to slide down the same into the channel below it instead of suddenly dropping 100 into said channel over an unsubmerged edge of the riffle. A sudden drop of the concentrates into a channel over a non-submerged edge of the riffle immediately above the channel is undesirable since the minerals in 105 the channel are thereby continuously agitated and more or less of them are continuously washed out of the channels and over the riffles below in succession down the slope 110 of the deck, whereas it is desirable to retain

in the channels all minerals caught therein and to guide them under the influence of the reciprocating movement of the table toward the concentrates discharge end of the 5. deck.

Wall 22 of each riffle is as important as wall 21 for the protection of the mineral in the channels to prevent the same from being washed out of the channels. The 10 width of the riffles, the sloping portions of their top surfaces and the submerged upper edges of the lower sides or walls of the riffles all contribute to direct the water contained in the pulp in practically a straight line or 15 sheet over the riffle tops and thereby substantially eliminate all excavating action of the water on the materials in the channels.

When the materials fed to the table are rich in minerals I may secure to the top flat 20 surface of the forward portion of each main riffle 17 a cap riffle 25 (Figs. 5, 6 and 7) to increase the height of the upper side of the riffle in order that the large amount of minerals may be more fully protected and 25 conveyed in the channels toward the mineral discharge end 13 of the deck, the length of each cap riffle being dependent upon the richness of the material being treated.

If desired I may also apply to the surface 30 of the plateau C shallow riffles 26, the rear ends of which about the terminals of the main riffles 17. These extension riffles serve to convey the minerals from the channels between the main riffles to the concentrates 35 discharge end of the deck.

What I claim is:

1. In a transversely inclined differentially reciprocating concentrating table the combination with a deck, of main riffles thereon 40 extending in the direction of travel of the minerals toward the mineral discharge end of the deck and having a portion of their

upper surfaces sloping downwardly toward the tailings discharge side of the deck and a flat portion substantially parallel with the 45 surface of the deck, each of said riffles having side walls substantially at right angles to the surface of the deck, the portion of each said riffle facing the feed side of the deck being greater in height than the opposite side thereof and the width of each riffle being substantially greater than the height thereof, the forward end of each said riffle being tapered to reduce its height and cap riffles on the flat portion of the upper 55 surface of the main riffles to increase the height of the upper vertical side walls of the riffles.

2. In a transversely inclined differentially reciprocating concentrating table, the combination with a deck, of main riffles thereon extending in the direction of travel of the minerals toward the mineral discharge end of the deck and having a portion of their upper surfaces flat and substantially parallel to the surface of the deck and a portion sloping downwardly toward the tailings discharge side of the deck, each of said riffles having side walls substantially at right angles to the surface of the deck, the portion 60 of each riffle facing the feed side of the deck being greater in height than the opposite side thereof and the width of the each riffle being substantially greater than the height thereof, and cap riffles on the flat portions 65 of the main riffles at the forward ends thereof to increase the height of the upper vertical side walls of the main riffles for the purposes described.

In witness whereof I have hereunto subscribed my name this 24th day of December, 1919.

EMIL DEISTER.
